CLAIM

The ornamental design for a carriage lever handle for toaster, as shown and described.

DESCRIPTION

FIG. 1 is a perspective view of a carriage lever handle for toaster showing my new design;

FIG. 2 is a front view thereof;

FIG. 3 is a rear view thereof;

FIG. 4 is a right side view thereof;

FIG. 5 is a left side view thereof; and,

FIG. 6 is a bottom view thereof.

The broken lines shown in the drawing is for illustrative purposes only and forms no part of the claimed design.
